UNITED STATES PATENT OFFICE.

JOHN SHEEHAN, OF MELBOURNE, VICTORIA, AUSTRALIA.

APPARATUS FOR DRAWING OFF AERATED WATERS.

1,176,103.

Specification of Letters Patent. Patented Mar. 21, 1916.

Application filed March 5, 1914. Serial No. 822,761.

To all whom it may concern:

Be it known that I, JOHN SHEEHAN, engineer, a citizen of the Commonwealth of Australia, and resident of Melbourne, State of Victoria, Commonwealth of Australia, (whose postal address is 32 Crossley street, Melbourne, in the State of Victoria, Commonwealth of Australia,) have invented certain new and useful Improvements in Apparatus for Drawing Off Aerated Waters, of which the following is a specification.

This invention relates to an apparatus for drawing off aerated waters in bars, restaurants, refreshment booths, and such like places. Hitherto with soda fountains and such like apparatus for drawing off aerated waters, the syrup or flavoring essence is first of all poured or tapped into the glass and the soda water from the carbonator vessel (in which the water is charged with compressed carbonic acid gas) is then directed into the said glass by means of a tap or valve.

The object of this invention is to provide means whereby the syrup and the soda water are discharged into the glass at the same time by the one operation of a valve or tap, producing thereby soda water or other like beverage of a better quality than hitherto, and in a more expeditious and economical manner. I accomplish this object by means of a special arrangement of a combined mixing and discharge tap or valve which is connected to a carbonator on the one hand (containing water charged with carbonic acid gas under pressure) and to a vessel containing syrup on the other hand also under pressure or at a sufficient height in such manner that by one operation of a handle or lever of the tap a quantity of syrup and a quantity of soda water is discharged into a glass or other receptacle. This tap may be so designed that optionally two distinct syrup valves may be operated whereby the same tap may be utilized for drawing off two distinct beverages.

This invention comprises broadly a syrup vessel under pressure (or at a sufficient height to provide a head) a carbonating vessel under pressure, and the combined mixing and discharging tap or valve connected to the two. This mixing tap or valve comprises one or more inlets for the syrup having controlling valves, an inlet for the soda water having a controlling valve, a chamber to contain a certain quantity of soda water, a

snifting valve for reducing the pressure of gas in the said chamber, means for causing the flow of soda water into the glass from the chamber at the same time as the flow of the syrup thereto.

The invention will now be more fully described aided by a reference to the accompanying sheets of drawings in which:—

Figures 1 and 2 show the general arrangement of the invention, Fig. 1 being where the syrup is forced upward by gas pressure and Fig. 2 where the syrup vessel is arranged at a sufficient height to provide pressure by gravity. Fig. 3 is an elevation of the syrup vessel. Fig. 4 a detail sectional view of the mountings on the neck of the syrup vessel. Fig. 5 is a detail section showing the means devised for attaching the gage or sight glass to the said vessel. Fig. 6 is a side elevation of a tap designed to draw off only one kind of beverage, the syrup valve being shown in section. Fig. 7 is a central vertical section of the tap illustrated in Fig. 6 showing the soda water controlling valve; and the valve arrangement for discharging the soda water into the glass. Figs. 8 and 9 are detail views of the soda water controlling valve. Fig. 10 is a vertical section of the snifting valve. Figs. 11 and 12 show a modified form of tap for drawing off alternatively two separate beverages. Fig. 13 is a sectional view of a modified form of valve to control the soda water.

Referring to these drawings A is the tap or valve attached to a bar counter, B the syrup vessel, C the carbonator and D the carbonic acid cylinder. In Fig. 1 the syrup vessel B, carbonator C and gas cylinder D, are shown as arranged in the cellar, the discharge of the soda water and the syrup being effected by the pressure of gas. In Fig. 2 the carbonator C and the gas cylinder D are shown in a position adjacent to the counter while the syrup vessel B is arranged at a sufficient height to supply the syrup by gravity. The tap A is connected to the syrup vessel B by the pipe B' and to the carbonator C by the pipe C'. In Fig. 1 the syrup vessel B and the carbonator C are connected to the gas cylinder D by the pipes B² and C² respectively, in order that the desired pressure of gas may be admitted to the said vessels B and C to force the liquid to the tap A. Suitable reducing valves and pressure gages B³ and C³ of well known con-

struction are mounted on the said cylinder D to regulate the pressure of gas to the respective vessels B and C.

The syrup vessel B (Figs. 3, 4 and 5) is preferably an earthenware jar having a gage or sight glass B⁴ mounted on its side for showing the quantity of syrup left therein. This sight glass B⁴ is mounted in sockets B⁵ or the like which are held in position by tubular bolts B⁶ (see Fig. 5) the heads of which are adapted to bear against the inside of the jar or vessel B while a nut B⁷ on the end of the said tubular bolt B⁶ enables the socket piece B⁵ to be forced tight against the side of the vessel as shown with suitable packing to make a liquid tight joint. The tubular bolt B⁶ is placed in position by being passed through the neck of the jar which is large enough to accommodate the head of the bolt when the bolt proper can be drawn through the wall of the jar B by any convenient means.

The neck of the jar or vessel B is furnished with a cap or head B⁸ which comprises a gas inlet valve B⁹ connected to the pipe B² leading to the carbonic acid gas cylinder D, a syrup outlet valve B¹⁰ connected to the pipe B' leading to the tap A and an ordinary safety valve B¹¹ for allowing any excess of gas pressure to escape from the said vessel or jar B. The said head or cap B⁸ is also fitted with a feeding orifice having a removable plug B¹² for filling purposes. The syrup outlet to the valve B¹⁰ is connected to a pipe or tube B¹³ which leads to within a short distance of the bottom of the jar or vessel B in order that the syrup may be forced up to the tap A by the pressure of gas.

The carbonator C is of ordinary construction mounted on a suitable frame having a mixing or agitating device operated by a handle C⁴ and is fitted with a gage or sight glass C⁵ and is connected to the tap A by the aforesaid pipe C' through which the soda water is forced. If desired the soda water pipe C' leading from the carbonator to the tap A may be connected to a cylinder C⁶ arranged in an ice box C⁷ situated under the counter or the like for the purpose of cooling the liquid before delivery. The said carbonator C is also connected to the reducing valve C⁸ on the gas cylinder D by the pipe C² as before stated and shown in Fig. 1.

The mixing tap or valve A may be constructed either as shown in Figs. 6, 7, 8, 9 and 10 which is designed for drawing off only one kind of beverage or it may be constructed as shown in Figs. 11 and 12 which is designed for drawing off alternately different beverages, and is therefore adapted to operate two distinct syrup valves. This tap comprises one or more syrup inlets which are connected to the syrup vessel B by the pipe B' and furnished with one or more

syrup valves A⁴, a soda water inlet A⁵ leading to the soda water valve A' and a port or passage A⁶ leading to a soda water chamber A⁷ adapted to contain a certain quantity of soda water.

The tap illustrated in Figs. 6 and 10 is designed for drawing off only one kind of beverage and is fitted with a rotary soda water controlling valve adapted to be operated by a horizontal lever A⁸. In Fig. 13 a modified form of such valve is shown which comprises a reciprocating valve spindle A²⁰ operated by a vertically arranged rocking lever A³ as shown in Figs. 11 and 12.

The rotary soda water controlling valve A' as shown in Figs. 7 and 9 comprises a flat disk mounted on the lower end of the vertical spindle A⁸ to which the operating handle A³ is attached. This valve A' is furnished with a port or passage A⁹ which is adapted to be placed in such a position that it connects the soda water inlet A⁵ with the port A⁶ both of which are in communication with the carbonator C by the pipe C', thereby enabling soda water to be forced from the carbonator C to the soda water chamber A⁷. In the bottom of the said chamber A⁷ is a spring actuated valve A¹⁰ which is adapted to be closed by the pressure of soda water thereon entering the chamber A⁷ through the port or passage A⁶ and the tube A¹¹ connected thereto and is opened when the pressure is released by the coiled spring A¹² which is mounted in the nipple A¹³ in the bottom of the chamber A⁷. This valve A¹⁰ is tubular, and furnished with horizontal ports or perforations A¹⁴ through which the soda water from the chamber A⁷ is discharged into the glass. This valve A¹⁰ as before stated is closed by the pressure of soda water causing the spring A¹² to be compressed and the ports A¹⁴ to be covered by the nipple A¹³, thus enabling the chamber A⁷ to be filled with soda water. When the pressure on the valve is released it is raised by the spring A¹² to the position as shown in Fig. 7 and at the same time allows the soda water to be discharged from the chamber A⁷ through the perforations or ports A¹⁴ and flow into the glass or the like at the same time as the syrup. This soda water valve A' as before stated is operated by the horizontal hand lever A³ (Fig. 6) in such manner that when the same is open the valve A¹⁰ in the bottom of the chamber A⁷ is closed preventing the flow of soda water through the glass, and the chamber A⁷ is in open communication with the carbonator C and is filled with soda water. In conjunction with this soda water inlet valve A' is a sniffling or pressure reducing valve A¹⁵ which is adapted to reduce the pressure of gas in the soda water in the chamber A⁷ when the flow thereto is shut off from the carbonator. This valve A¹⁵ is constructed

as shown in Fig. 10 and adapted to be opened by a tappet arm A^{16} on the horizontal handle A^3 and closed by the coil spring A^{17} . The pressure of gas in the chamber A^7 is discharged through the passage a' and the pipe a^2 to atmosphere or to the ice chamber.

The syrup valve A^4 is arranged upon the side of the soda water chamber A^7 and constructed as shown in Fig. 6. The valve is held up against the seat in the casing by means of a coil spring in order to govern the flow of syrup to the glass through the port or passage b and the tube b' . To regulate the quantity of syrup being delivered a screwed spindle valve B^{14} is provided to regulate the size of the syrup passage connecting the chamber of the valve A^4 with the pipe or tube B' leading to the syrup vessel or jar B .

20 The tappet arm A^{16} on the lever A^3 which operates the syrup valve A^4 and snift valve A^{15} is furnished with two contacting faces A^{18} and A^{19} —the face A^{18} adapted to operate the snift valve A^{15} and the face A^{19} adapted to operate the syrup valve A^4 . The said tappet arm A^{16} is so designed that by the handle A^3 being operated a given distance only the soda water valve A^7 and the snift valve A^{15} are operated, thereby allowing only soda water to flow into the glass, but by moving the said handle to the end of its stroke the syrup valve A^4 is operated and syrup is allowed to flow into the glass with the soda water.

35 The modified form of soda water valve shown in Fig. 13 which is preferably used when two syrup valves A^4 are employed comprises a perforated valve A^2 having a transverse opening A^{20} therethrough. A 40 perpendicularly disposed circular opening A^{31} is also provided therein crossing the said opening A^{20} and in which a reciprocating spindle A^{20} is loosely mounted, on the lower end of which is mounted a closure member A^{21} for the said valve A^2 , the said closure member A^{21} being kept in contact with the valve A^2 by a coiled spring A^{22} mounted within the chamber A^{23} . That portion of the spindle A^{20} passing through the valve A^2 is made of flat or triangular shape in cross section as at A^{32} , thereby forming passages about the same which when the said spindle A^{20} is depressed or forced down opening the valve by downward movement 50 of the closure member the soda water passes through the valve into the chamber A^{23} and thence into the soda water chamber A^7 through the passage A^6 and pipe or tube A^{10} . This type of valve is operated by the 55 vertically arranged handle A^3 shown in Figs. 11 and 12 having a cam shaped projection A^{24} which when the handle is in a vertical position as shown in Fig. 11 the projection A^{24} contacts with the spindle and forces the same down and opens the valve.

The syrup valves A^4 are operated by cams E and E' mounted on the said handle A^3 while the snifting valve A^{15} is operated by a cam face or recess E^2 formed in the side or inner face of the cam E . Thus by operating the handle A^3 in a forward direction as indicated by the arrow one syrup and soda water is discharged into the glass, while by operating the handle A^3 in a backward direction another syrup and soda water is discharged, giving two separate beverages as indicated by the outer dotted lines in Fig. 11. When the handle is in a vertical position shown in Fig. 11 the soda water chamber A^7 is in communication with the carbonator C and is filled with soda water, then by moving the handle forward to a position indicated by the inner forward dotted line the soda water valve A^7 is released and the snifting valve A^{15} is operated by the cam face or recess E^2 without the cam faces E and E' contacting with the syrup valves, thus soda water only may be discharged.

I claim—

1. In an apparatus of the character described, a carbonator, a chamber normally in communication with the carbonator, a manually operated valve for cutting off communication with the carbonator, a snift valve adapted to be operated to reduce the pressure in the said chamber, when cut off from the carbonator, a syrup valve adapted to be operated by the same handle which actuates the carbonator valve, and an independent 100 automatic spring valve, provided at the bottom of said chamber adapted to permit the flow of soda water therefrom when the said carbonator valve is closed.

2. In an apparatus of the character described, a carbonator, a chamber normally in communication with the carbonator, and adapted to receive a predetermined amount of soda water therefrom, a manually operated valve for cutting off communication 110 with the carbonator, a handle adapted to operate said valve, a snift valve adapted to be operated to reduce the pressure in the said chamber when cut off from the carbonator, a syrup valve, means carried by the said handle adapted to open said syrup valve upon movement of the said handle, and an independent automatic spring valve provided at the bottom of said chamber adapted to permit the flow of soda water therefrom when 120 the said carbonator valve is closed.

3. In an apparatus of the character described, a carbonator, a chamber normally in communication with the carbonator and adapted to receive a predetermined amount 125 of soda water therefrom, a manually operated valve for cutting off communication with the carbonator, a handle adapted to open the said valve, a snift valve for reducing the pressure in the said chamber when 130

cut off from the carbonator, means carried by said handle adapted to operate said snift valve, after communication is cut off between the carbonator and the said chamber, 5 a syrup valve, means carried by said handle adapted to open said syrup valve upon movement of the said handle, and an independent automatic spring valve provided at the bottom of said chamber adapted to permit the 10 flow of soda water therefrom when the said carbonator valve is closed.

4. In an apparatus of the character described, a carbonator, a chamber normally in communication with said carbonator, and 15 adapted to receive a predetermined amount of soda water therefrom, a manually operated valve for cutting off communication with the carbonator, a spring pressure valve provided at the bottom of said chamber having 20 ports therein adapted to empty the soda water from said chamber when the carbonator valve is closed, the said spring pressed valve being provided with a bowled portion and adapted to be closed during opening of 25 the carbonator valve, by the pressure exerted on the said bowled portion.

5. In an apparatus of the character described, a carbonator, a chamber adapted to hold a predetermined amount of soda water, 30 a valve adapted to normally maintain the said chamber in communication with said carbonator, the said valve comprising a closure member, a spring bearing on said closure member, and a reciprocating spindle 35 engaging said closure member, and adapted to open the same against the force of the said spring by pressure being exerted thereon, a handle provided with a cam surface adapted to normally exert a pressure on said 40 spindle to maintain the said valve open, and to release said spindle upon operation of the handle to close the valve, a snift valve adapted to be operated to reduce the pressure in the said chamber, when cut off from the 45 carbonator, a syrup valve adapted to be operated by the same handle which actuates the carbonator valve, and a valve provided at the bottom of said chamber, adapted to per-

mit the flow of soda water therefrom when the said carbonator valve is closed. 50

6. In an apparatus of the character described, a carbonator, a chamber normally in communication with the carbonator and adapted to receive a predetermined amount of soda water therefrom, a manually operated valve for cutting off communication with the carbonator, a handle adapted to operate said valve, a snift valve adapted to be operated to reduce the pressure in the 60 said chamber when cut off from the carbonator, a syrup valve, means to open the snift valve, the same means carried by the said handle adapted to open said syrup valve upon movement of the said handle, means adapted to control the flow of syrup to said 65 syrup valve, and an independent automatic spring valve, provided at the bottom of said chamber adapted to permit the flow of soda water therefrom when the said carbonator valve is closed. 70

7. In an apparatus of the character described, a carbonator, a chamber normally in communication with the carbonator and adapted to receive a predetermined amount of soda water therefrom, a manually operated valve for cutting off communication with the carbonator, a handle adapted to operate said valve upon each movement thereof, a snift valve adapted to be operated to reduce the pressure in the said chamber 75 when cut off from the carbonator, a plurality of syrup valves, means carried by said handle adapted to separately operate said valves upon movement in different directions, and an independent automatic spring 80 valve provided at the bottom of said chamber, adapted to permit the flow of soda water therefrom when the said carbonator valve is closed. 85

In testimony that I claim the foregoing 90 as my invention, I have signed my name in presence of two subscribing witnesses.

JOHN SHEEHAN.
